FIG. 5.

FIG. 6.

BENJAMIN WEISS
Inventor

By his Attorney Julian J. Wittal

UNITED STATES PATENT OFFICE.

BENJAMIN WEISS, OF NEW YORK, N. Y.

AUTOMATIC DRIP-PAN ALARM.

Application filed May 28, 1925. Serial No. 33,391.

To all whom it may concern:

Be it known that I, BENJAMIN WEISS, a citizen of the United States, and resident of New York, in the county of New York and State of New York, have invented certain new and useful Improvements in Automatic Drip-Pan Alarms, of which the following is a specification.

This invention relates to drip pan alarms and is an improvements over the invention disclosed in my copending application Serial Number 732,895, filed August 19, 1924. In said application, the alarm mechanism is driven by a spring which must be manually wound up and should the operator forget to wind up the spring, the alarm mechanism is ineffectual. It is a primary object of the present invention to provide an alarm mechanism that is automatically wound up, thus doing away with the necessity of manually winding up the same.

It is a further object of the invention to provide an alarm that is simple in construction and positive in operation.

Other objects and advantages will appear as the description proceeds.

In the accompanying drawing forming a part of this specification,

Fig. 1 is a front elevation of my improved alarm with parts removed and others shown diagrammatically.

Fig. 2 is a side elevation of the improved alarm.

Fig. 3 is an enlarged detail view of the gear controlling means forming part of the invention.

Fig. 4 is a bottom plan view showing the alarm attached to a drip pan, most of its parts being removed.

Figs. 5, 6, and 7 are various sectional views of a modified form of applying my alarm device to a drip pan, while

Fig. 8 shows in a semi-diagrammatical manner and at a reduced scale the side view of a drip pan with the modified form of my alarm device thereon.

Referring to the views of the drawing in detail, an alarm mechanism is confined in a housing 10 preferably formed of metal. This housing 10 is substantially rectangular in shape with shouldered portions adjacent its top. Formed in the sides of the housing 10 and extending longitudinally thereof from the bottom of the shouldered portions to the bottom of the housing are depressions

or guide ways 11. Mounted on the rear of the housing is a flat supporting bar 12, with its vertical portion riveted or otherwise fixed to the rear of the housing 10 and its free horizontal portion extending rearwardly of the housing and adapted to support a drip pan 13 in a manner similar to that described in my aforesaid application. A flat bar 14 with hooked ears 15 is slidably and adjustably mounted in channel ways 15' formed on the rear of the housing. This bar and channel way arrangement permits the vertical adjustment of the housing 10 to fit any size pan 13.

The alarm mechanism is contained in said housing 10. This mechanism is mounted on a plate 16, of the same shape as the housing 10 and formed with shouldered portions similar to the shoulder portions of said housing, and with which they are adapted to cooperate when in operative position. Extending rearwardly of the plate 16 and disposed centrally thereof at its bottom is a flanged portion 17 provided with an opening 18. Formed in said plate 16, by punching the same, at a point just beyond its middle portion and in line with the flanged portion 17, is another rearwardly extending flange portion 19, having an opening 20 in line with the opening 18 in the flange 17. Said flange 19 leaves an opening 21 as will be more clearly seen from Figure 3.

Secured to said plate 16, on the side opposite to said flange portions, is a bearing plate 20' having an offset portion 21' extending almost to the top of said plate 16. Mounted on the outside surface of this plate 21' is a signal bell 22 which it is the purpose to ring upon the filling of the pan 13 to a predetermined height. The gearing for ringing the bell 22 is disposed between the plates 16 and 20'. This gearing comprises a main drive gear 23 mounted rotatably on a stud 24 extending between said plates 16 and 21'. Said main drive gear 23 drives the gears 25 and 25' mounted on a shaft 26 journalled in said plates 16 and 21'. The gear 25' drives through the intermediacy of gear 27', a star wheel 27 revolvably mounted on a shaft 28 extending between said plates 16 and 21'. The teeth of said star wheel 27 are in line with and are adapted to engage a rocker member 28 mounted on a shaft 29. Rigidly secured to said rocker member 28 is a hammer 30 which is adapted to strike

the bell 22 upon being rocked by said member 28, thereby ringing the same.

The motive force for actuating the train of gearing for ringing the bell is a curved spring 31. Said spring 31 is coiled around a stud 32 secured to the plate 16 and extends across the top of plate 21'. Mounted on the pin 24 and disposed between the drive gear 23 and the plate 16 is an arm 33. This arm 10 33 is mounted to rock independently of the gear 23. Carried on a stud mounted adjacent the lower end of said arm 33 is a pawl 34, the nose of which pawl is adapted to engage the teeth of gear 23 to drive it in a 15 counter clockwise direction. Said pawl is normally urged into engagement with said gear by means of a spring 35. Also mounted near the lower end of said arm 33, adjacent the pawl 34, is a stud 36 formed with a circumferential groove 37 near its top. Said stud 36 passes through the arm 33 and has secured thereto between the arm 33 and the plate 16 a bail 38. Normally the spring 31 20 will exert a force on the gear 23 to the right of its center line, thereby driving said gear 23 in a counter clockwise direction and ringing the bell.

The movement of the train of gearing is stopped as follows. Pivotaly mounted on 30 the surface of the plate 16 carrying the flange portions 17 and 19, is an arm 39 (Figs. 2 and 3). Said arm terminates in an offset or flanged portion 40, the side of said flanged portion 40 nearest the opening 21 slopes to 35 a point as indicated at 41, for a purpose which will be explained. Rigidly secured to said arm 39 and disposed at an acute angle thereto is a rod 42. This rod 42 is formed with an offset portion 43 which is adapted 40 to pass through the opening 21 from one side of the plate 16 to the other side thereof, and with a flattened end as will be seen from Figure 2. When the arm 39 is in normal 45 position, the flattened end of the rod 42 is in the line of movement of the one of the two studs 44 carried on each side of driven gear 25' on the face thereof nearest the plate 16. Said arm 39 is steadily urged into locking 50 position by means of an elongated spring 45. When said rod 42 comes into contact with either of said studs 44 the rotation of the gears stops as will be understood.

Extending between the flanged portions 17 and 19 of the plate 16 is a post 46, the upper portion of which is formed into cammed ribs 47. Encircling said post 46 is a spring 48, the bottom coil of which is seated on a rod 49 carried by said post 46. Said rod is formed with an offset portion 50 which is 55 adapted to pass through an elongated slot 51 to the opposite side of plate 16, the protruding end of said offset portion 50 being provided with a circumferential groove 52, in which latter groove the lowermost portion 60 of the bail 38 is adapted to rest. The upper

coil of said spring 48 rests against the under surface of flanged portion 19 which provides a stationary seat therefor.

The operation of the device is as follows: Assuming that the spring 31 engages the stud 36 when said stud with its supporting arm 33 is in its farthermost position to the left as seen in Figure 1. If the pan 13 is filled with water to such an extent that the weight of the same presses the pan downwardly, the housing 10 by reason of its shouldered portions engaging the shouldered portions of the plate 16 will press said plate 16 with its associated parts downwardly over the post 46, which forms the third leg of a three legged support for the pan as described in my copending application, against the action of the compression spring 48. When the pointed side of the flanged portion 40 of the arm 39, which pointed side is in line with the edges of the cammed ribs 47, meets the upper cammed rib 47, the arm 39 is given a lateral movement and the rod 42 carried thereby is rocked from engagement with the stud 44, thereby permitting the rotation of the gearing under the force of the spring 31. As soon as the flanged portion 40 passes the upper cammed rib 47 it slides into the groove between said upper rib and the next rib and the arm 39 returns to its normal position, placing the rod 42 in line with the stud 44. When the water reaches another predetermined level in the pan 13, the flanged portion 40 reaches the second cammed rib 47 with the same result, and so on when the flanged portion reaches the third and last rib 47. Each time the gearing is released for motion, the bell rings, as will be understood. When the third and last warning is sounded and the pan is removed and emptied, the housing 10 with the plate 16 and its associated parts ride upwardly over the post 46 to their normal positions. Upon said upward movement of said parts, the arm 33 with its pawl 34 is carried in a clockwise direction to its initial position which is about centrally of the plate 16, where it is again in position to force the gear 23 around. By reason of this construction, there is no necessity for manual regulation of any of the parts and the alarm mechanism is automatically placed in position for effective work. A pin 53 on post 46 and cooperative slot 54 in plate 16 serve to further guide and steady the movements of post 46.

The modification shown in Figs. 5 to 8 relates only to the means employed for securing my device on a drip pan and for supporting the same on the ground, while the improved alarm mechanism itself and its operation remain exactly the same as has been described hereinbefore.

In this modification my alarm mechanism is arranged in a housing 70 preferably made

- of cast metal, like brass, aluminum, etc., having all of its sides and top closed while the bottom of the same is left open in order to insert the mechanisms thereinto and permit them to contact with the ground. The front side 71 of the housing 70 is made curved to conform with the curvature of the drip pan and two small vertical ribs 72 are cast in the inside of both side walls forming a groove 73 between them adapted to receive the main holding plate 74 of my mechanism. The holding plate 74 plays in this case the same rôle as the plate 16 played in the preferred embodiment described hereinbefore and has the cut out and rectangularly bent portion 75 as well as additional members, and plate elements 76 and 77 secured thereto for supporting and securing the same elements of my alarm mechanism proper, and in the same manner, as has been described hereinbefore. The bent plate 76 is employed in this case for supporting the bell 78 which is arranged outside of the housing 70 in order to make said housing smaller and to give the bell a louder tone. The main supporting plate 74 has a rectangularly bent lower end 79 adapted to engage the bottom 80 of the drip pan 81 and projecting thereunder. Two wire hooks 82 engage the top rim 83 of the drip pan 81, their vertical stems passing through the top 70 of the casing and down through the space inside of the same. Two long sleeve nuts 84 engage the rectangular bend 79 and receive the threaded lower ends 85 of the hooks 82. It is obvious that upon turning the sleeve nuts 84 the wire hooks 82 will be securely pressed against the top of the drip pan and not only the housing 70 will be firmly secured on the drip pan through the rectangular bend 79, but the pressure of the sleeve nuts 84 on said rectangular bend will also secure the inside mechanism of my alarm device in its place. It will be seen, that both, the housing of my mechanism on the drip pan and the mechanism in said housing may be secured by driving home the two sleeve nuts 84 and they may be removed and dismantled by simply removing said two sleeve nuts.
- The alarm mechanism proper is arranged within the housing 70 in a similar manner as hereinbefore and operates the same way through the intermediacy of plunger 86. In order to give a simplified support for the drip pan and an improved movement for my alarm mechanism when it is caused by the weight of the water to slide downwardly over the plunger 86, I however provide in this modification two ground contacting, supporting and guiding members or legs 87, instead of letting the plunger 86 itself rest on the ground. These legs are secured near the two ends of a cross bridge member 88, preferably made of pressed sheet metal, and the center of which is firmly secured to the lower end of plunger 86, by the rivet 89, or by any other suitable means. Two holes are provided in the rectangular bend 79 to permit a free play of the legs 87 therethrough and said rectangular bend 79 also provides a lowermost limit to the movements of bridge 88. The spring 48, described hereinbefore acts on said bridge 88.
- In this modification the legs 87 provide two supporting points for the drip pan 81, as shown in Fig. 8, while the third supporting point for the drip pan is provided by the point 90 of its bottom circumference directly opposite to said legs 87. The weight of the water dripping into the pan will have a larger effective arm to act upon the alarm mechanism than it had in the preferred embodiment, described hereinbefore.
- I want to emphasize that the terms and expressions employed are used as terms of description and not of limitation and I have no intention, in the use of such terms and expressions, of excluding any equivalents of the features shown and described, but recognize that further embodiments may be possible within the scope of the invention claimed.
- I claim:
1. In combination with a drip pan, a signalling device secured to said pan and mounted on a support, said signalling device being adapted to slide downwardly on said support under the weight of the liquid in said pan; an elastic member interposed between said signalling device and said support to return said signalling device into its original position when the liquid is removed from said pan; a source of power adapted to operate said signalling device; means to normally check the operation of said power, and means to intermittently release said checking means upon the signalling device reaching predetermined positions on the support.
  2. A signalling device for drip pans comprising means responsive to the force of increasing weight allowed to enter said pan, said means including an extensible support on which the pan rests, an alarm mechanism carried by said support and actuated by the lowering of said pan under the weight of the water therein, a source of force for activating said alarm device and means for automatically returning said source of force to effective position upon the removal of said weight.
  3. In an alarm device; a stationary element and a movable element, an outside force acting upon said movable element; the changing phases in the operation of which is to be signalled by said alarm device; a source of force to actuate said alarm device upon predetermined positions being reached by said movable element; an elastic element interposed between said moving element and

- said stationary element and being influenced by their relative movement, and means connected with said elastic element to return said alarm actuating force into its original condition ready to actuate said alarm upon said outside force being removed and said elastic element being released.
4. In combination with a liquid receptacle, like an ice box drip pan, an alarm mechanism secured to said receptacle and slideable upon a support under the action of the weight of the liquid received by said receptacle; a source of force to operate said alarm normally checked but intermittently released at predetermined relative positions of said alarm upon said support; an elastic member interposed between said alarm device and said support and influenced by their relative movement, and means connected with said elastic member to return said alarm operating force into its original normal condition ready to again operate said alarm when the liquid is removed from said receptacle and said elastic member is released.

5. In combination with a liquid receptacle, like an ice box drip pan, a support for said receptacle, it being slideable thereon under the action of the weight of the liquid; an alarm device secured to said receptacle and slideable on said support therewith; an elastic member interposed between said alarm device and said support and being influenced by their relative movement; a source of force adapted to actuate said alarm device but normally prevented from

operation by checking means; means to remove said checking means upon said alarm reaching predetermined positions, and returning means in connection with said elastic means to return said source of force into its original condition ready to again operate said alarm upon the liquid being removed from said receptacle and said elastic member released from its action.

6. In combination with a liquid receptacle, like an ice box drip pan, an alarm device secured to said receptacle; a support for said receptacle, said alarm device being slideable on said support under the influence of the weight of the liquid received by said receptacle; a spring normally urging said alarm device into operation; a movable element normally engaging the said alarm device and preventing its operation; means to intermittently move said element to operate upon said alarm reaching predetermined positions on said support, and means to thereafter return to its checking position; an elastic element between said alarm device and said support influenced by the weight of the liquid in said receptacle, and a connecting member between said alarm operating spring and said elastic member adapted to return said spring into its original position when said elastic member is released from the influence of the weight of the liquid in said receptacle.

Signed at New York, in the county of New York, and State of New York this 19th day of May, A. D. 1925.

BENJAMIN WEISS.
